UNITED STATES PATENT OFFICE.

BAINBRIDGE W. BURDICK, OF ALBANY, NEW YORK.

DESIGN FOR A PLATE-KEEPER SHELL.

SPECIFICATION forming part of Design No. 28,762, dated May 31, 1898.

Application filed March 4, 1898. Serial No. 672,608. Term of patent 14 years.

To all whom it may concern:

- Be it known that I, BAINBRIDGE W. BURDICK, a citizen of the United States, residing at Albany, in the county of Albany and State 5 of New York, have invented and produced a new and original Design for a Plate-Keeper Shell, of which the following is a specification, reference being had to the accompanying drawings, forming part thereof.
- 10 Figure 1 is a perspective view of a plate-keeper shell showing my new design, viewed from its outer side. Fig. 2 is a side elevation of the boss and its plate, viewed from an end thereof.
- 15 As shown in the drawings, the leading and material features of my design consists in a shell having the shape or configuration comprising a boss A, projected outwardly from the face-surface of side B, and an angularly- 20 projected side C, disposed or arranged as

shown in the drawings, the surface of side B being flat and plain and forming the field from which the boss A is raised, and the boss A itself being plain in its surfaces and standing prominently or boldly out from such field, 25 while the side portion C is horizontal and is shown to be projected in direction opposite to the direction of projection of said boss and having its upper surface left plain at an angle to the face-surface of the side B, from 30 which the said boss is projected.

Having described my invention, what I claim as new, and desire to secure by Letters Patent, is—

The design for a plate-keeper shell as herein 35 shown and described.

BAINBRIDGE W. BURDICK.
